ATTORNEY

UNITED STATES PATENT OFFICE.

MICHAEL J. DUNN, OF PHILADELPHIA, PENNSYLVANIA.

PIANO CONSTRUCTION.

1,301,825.

Specification of Letters Patent. Patented Apr. 29, 1919.

Application filed August 31, 1917. Serial No. 189,159.

To all whom it may concern:

Be it known that I, MICHAEL J. DUNN, a citizen of the United States, residing at 2750 N. 24th St., Philadelphia, in the 5 county of Philadelphia and State of Pennsylvania, have invented new and useful Improvements in Piano Construction, of which the following is a specification.

This invention relates to pianos, and has 10 for an object to render removable certain elements of a piano which have hitherto been of a permanent character, in order that the piano will be capable of being dexterously manipulated through narrow, restricted hall 15 and doorways or the like, so that the same may be removed from or positioned within a room with ease and convenience.

Another object of the invention is to provide a piano wherein the foot and truss bars 20 of the same are of a readily removable nature, whereby when said bars are removed from the piano, the latter may be easily handled in limited areas.

For a further disclosure of the invention, 25 reference is to be had to the following description and to the accompanying drawings, the latter forming a part of the present specification and in which—

Figure 1 is a fragmentary sectional view 30 of the piano, embodying the features of the present invention.

Fig. 2 is a vertical sectional view taken along the line 2—2 of Fig. 1, disclosing more 35 clearly the means for removably securing one of the foot bars or toe pieces of the piano with the casing or body of the latter.

Fig. 3 is a horizontal sectional view taken along the line 3—3 of Fig. 1, and

Fig. 4 is a diagrammatic view illustrating 40 the method of positioning a piano, constructed in accordance with the invention, in a room adjoining a relatively narrow hallway.

Similar characters of reference denote 45 corresponding parts in all the views of the drawing.

In order that the aims and achievements 50 of the invention may be clearly understood, it is thought advisable to state at this juncture that heretofore considerable difficulty has been encountered by piano movers in passing pianos through an average proportioned hall or doorway, this being due to the limited area of the latter with regard to the 55 rather bulky nature of an average piano. When difficult conditions of this character

are encountered, piano movers have usually been obliged to remove the piano action and keyboard construction, so as to decrease the general width of the piano, so that the latter 60 may be turned and twisted around sharp corners, common to a usual sized hallway. This removing of the aforesaid parts of the piano by unskilled persons is frequently detrimental to the operative condition of the 65 piano, inasmuch as it requires expert workmen to properly replace the same. Moreover, under certain conditions doorways have to be enlarged to permit of the passage of a piano therethrough, thus necessitating 70 considerable expense and trouble, due to the tearing away of the plaster and framework of a door. To avoid these objections, and others, the present invention contemplates providing a piano 1, wherein is provided the 75 usual body or casing 2, and a keyboard 3, with removable foot bars or toe pieces 4, and to likewise render removable the associated truss elements 5, in order that the piano may be successfully manipulated while 80 positioned within a narrow hallway or the like.

To this end the foot bars 4, only one of which having been shown, are provided with elongated inwardly extending portions 6, 85 which are adapted to lie within the casing 2. Ordinarily these extended portions are secured to the piano by means of tenon joints, glue, and inaccessible securing elements, so that the removal of these bars is rendered 90 impracticable. However, the present invention contemplates providing the inner face of each of the portions 6 with a dovetailed groove 7, the latter being adapted to receive a dovetailed, tapering bar 8, which is rigidly 95 secured to the body 2 by means of screws or the like 9. A ledge 10 is also secured to the body 2 at a position immediately above the upper edge of each of the foot bars 4, and is employed to guide the latter, when the same 100 is being inserted into the piano, and to generally strengthen the construction. It will be noted that the bar 8 tapers outwardly so that when the foot bar 4 is forced inwardly along the same, a substantial and efficient 105 method will be provided for effecting the association of the same with the piano, and one which will involve maximum strength. Other securing screws 11 are passed through the bar 4 and into the member 8, to prevent 110 undue outward movement of said bar. The latter is further provided with a shoulder 12,

which is adapted to engage the bottom board 13 of the piano, in order to limit the inward sliding movement of the foot bar. Thus it will be seen that there is provided an efficient method for securing each of the foot bars 4 to the piano 1. The construction permits the foot bars to be readily inserted into an operative position, and also permits the same to be easily disconnected and removed.

10 Each of the truss members 5 is rigidly secured to the foot bars 4, so as to provide a unitary construction, and the upper extremities of the truss members are provided with rigid securing plates 14, the latter being connected with the truss members through the medium of securing screws 15. The plates 14 are of a substantially greater width than the members 5 and are provided with openings for the reception of the headed 15 ends of screws 16, which are adapted to enter the keyboard 3, and are so positioned as to be easily accessible. Thus, in operation when it is desired to remove the foot or toe bars 4 and their associated truss members, 20 the screws 11 are removed from engagement with the bar 8, also, the screws 16 are removed from engagement with the keyboard 3. Thus it will be seen that by exerting an outward force upon the connected foot bar 25 and truss construction, the latter elements may be removed from connection with the piano in a simple and efficient manner.

The advantages derived by removing the members 4 and 5 have been clearly illustrated in Fig. 4 of the drawing, wherein has 30 been conventionally illustrated a hallway 17, adjoining a room 18, a doorway 19 connect-

ing the room with the hallway for communication. When it is desired to position a piano within the room 18, the piano is carried edgewise through the hall 17 and is positioned near the doorway 19. Now it will be seen that if the bars 4 and the truss members 5 were carried by the piano, it would be impossible to manipulate the latter 40 through the doorway 19. However, as shown, when the elements 4 and 5 are detached from the piano, the latter may be swung around on an axis, clearing the corners of the entrance 19 and thereby enabling 45 the piano to be inserted into the room 18, this feature having been clearly illustrated by broken lines in the drawing. It will be appreciated that minor alterations may be made in the means for removably securing 50 the members 4 and 5 upon the piano 1, and therefore I do not wish to be limited to the precise method illustrated and described, but what I desire to secure by Letters Patent is:

1. In a piano, a toe piece carried thereby, having one extremity thereof formed with a groove, a bar rigidly connected with said piano and operable to be positioned within said groove, and means for retaining said toe piece in a secured position upon said bar.
2. In a piano, a toe piece carried thereby, means for slidably securing said toe piece to said piano, a truss connected with the outer extremity of said toe piece, and means for removably securing upper end of said truss to said piano.

In testimony whereof I affix my signature.
MICHAEL J. DUNN.
